UNITED STATES PATENT OFFICE.

FRANZ PFAFF, OF ALTWASSER, GERMANY, ASSIGNOR TO ALFRED DUHRSEN, OF BERLIN, GERMANY.

DESIGN FOR A DECALCOMANIA SHEET.

Application filed July 9, 1923. Serial No. 6,737. Term of patent 7 years.

To all whom it may concern:

Be it known that I, FRANZ PFAFF, a citizen of the Republic of Germany, residing at Altwasser, in Silesia, Germany, have invented a new, original, and ornamental Design for a Decalcomania Sheet, of which the following is a specification, reference being had to the accompanying drawing, forming part thereof.

The figure is a plan view of a decalcomania sheet showing my new design.

I claim:—

The ornamental design for a decalcomania sheet, as shown.

FRANZ PFAFF.
